U.S. Cl. D48—31

FIG. 1

FIG. 2

FIG. 4

FIG. 3

FIG. 1 is a perspective view of the front of a luminaire showing my new design;

FIG. 2 is a perspective view of the rear of the luminaire of FIG. 1;

FIG. 3 is a front side view in elevation of the luminaire of FIG. 1; and

FIG. 4 is a view in elevation of the right side of the luminaire of FIG. 1.

To the extent that details are not shown, both lateral sides of the luminaire are essentially identical, mirror images of one another.

I claim:

The ornamental design of a luminaire, substantially as shown and described.
